UNITED STATES PATENT OFFICE

WILLIAM JOHNSON PAYNE, OF PANTHER BURN, MISSISSIPPI.

MECHANICAL MOVEMENT.

1,278,734.

Specification of Letters Patent. Patented Sept. 10, 1918.

Application filed September 13, 1917. Serial No. 191,159.

To all whom it may concern:

Be it known that I, WILLIAM JOHNSON PAYNE, a citizen of the United States, and a resident of Panther Burn, in the county of Sharkey and State of Mississippi, have invented a new and Improved Mechanical Movement, of which the following is a full, clear, and exact description.

My invention relates to mechanical movements particularly adaptable for obtaining a reciprocating motion. An object of the invention is to obtain a simple and inexpensive movement which is particularly adapted to jacks.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is an elevation of a jack provided with an embodiment of my invention;

Fig. 2 is a longitudinal section thereof on line 2—2, Fig. 1;

Fig. 3 is a diagram of the relative position of the moving parts constituting the mechanical movement;

Fig. 4 is a similar view to Fig. 1, showing a modified arrangement;

Fig. 5 is a modified view of a transmission for the jack, the same being shown in section;

Fig. 6 is an elevation of a modified jack in which the housing is separate from the base and wherein both the base and the post are movable; and

Fig. 7 is an edge elevation of the jack.

Referring to the drawings, 5 is the post, which is housed and guided by the casing 6. When the post 5 is used for jacking purposes the casing 6 is constructed accordingly and a head 7 is provided on the post 5. A stud 8 secured to the post projects through a slot 9 in the casing 6. A gear 10 is mounted eccentrically on said stud 8. It meshes with an idler 11 which is also in mesh with a gear 12 similar to gear 10 and mounted eccentrically on a shaft 13 and constrained to revolve therewith. The idler 11 is revolved

on a stud 14 secured to a link 15, the ends of which are pivotally connected to the centers of the gears 10 and 12.

As the shaft 13 is revolved, the gear 12 is revolved therewith from the position shown in dotted line in Fig. 3. In consequence the idler 11 is revolved and moved longitudinally, causing the revolution of the gear 10 from the position shown in dotted line, and also a longitudinal displacement of same. The two movements control the displacement of the stud 8 in the slot 9 and, therefore, the movement of the post 5. In cases where the post 5 is the rod of a pump the motive power can be applied directly to the shaft 13 without any other transmission, but in cases where the post 5 carries a gear 76 head a transmission is interposed for obtaining maximum capacity. The transmission can also be used in connection with a pump, if so desired, and it is formed of a series of gears, of which gear 16 is constrained to revolve with the shaft 13. The gear 16 meshes with a gear 17 with which a gear 18 is constrained to rotate. The gears 17 and 18 are mounted to revolve on a stud 19 carried by a hand wheel 20 which is, in turn, revolubly mounted on the shaft 13.

In cases where the mechanical movement is utilized for pumping purposes in place of a hand wheel, a pulley or other similar element may be substituted. The gear 18 is in mesh with a gear 21 concentric with the gear 16 and secured to the casing 6. In revolving the hand wheel 20 the gears 17 and 18 carried thereby are caused to revolve on their stud 19 due to the engagement of the gears 18 and 21. The rotation of the gear 17 on its stud causes the revolution of the shaft 13 through the medium of the gear 16 which is in mesh with the gear 17. The displacement of the shaft 13 causes the displacement of the gear 12, in consequence of which a longitudinal displacement is imparted to the post 5.

The mechanical movement may be provided without the idler 11 therebetween, but the advantage of the idler is that it makes the movement self-locking for any position, for the resultant of the forces acting between the two eccentric gears or cams and the intermediate idler is vertical and passes through the center of the operating shaft.

In the modified structure shown in Fig. 4 the stud 14' on which the pinion 11' bears extends through a slot 9' provided in the housing 6' of the jack. This stud 14' is secured to lazy tongs 24 disposed within the housing below the post 5' and to which the upper end of the tongs is connected by means of a stud 8', also bearing in the slots 9', the lower end of the tongs being secured to the shaft 13' which forms the abutment or reaction for the weight carried by the base.

In rotating the eccentric gears the link 15' is entrained and the stud 8' is caused to move in the slot, carrying therewith the upper end of the lazy tongs, the pin 14' also entraining that part of the lazy tongs to which it is connected, thereby the weight supported by the post is not only supported by the stud 8' but also by the pin 14' and shaft 13' to which the tongs are connected.

In Fig. 5 a modified form of transmission is shown, in which the pin 19' is carried by a gear 22 which is revoluble on the shaft 13''. The casing 6'' has an additional stud shaft 23' on which the hand wheel 20' is mounted and which carries a pinion 24' constrained to revolve therewith and in mesh with the gear 22. This arrangement permits a larger capacity of the jack.

In the modification disclosed in Figs. 6 and 7 the casing 26 is separate from the base 27. The eccentric gears and the transmission are mounted on a casing 26. The lower end of the lazy tongs 24'' is anchored to an extension of the base which enters the housing. The upper end of the lazy tongs is connected to the post 5'' through the medium of the stud 8'', and the central part of the lazy tongs is anchored to the shaft 13'', the stud 14'' being connected to the lazy tongs. The operation of the jack displaces the stud 8'' which entrains the lazy tongs; and since there are also tongs at both sides of its anchoring point, not only the post will move out of the casing 26 but also the casing will move off the base 27.

I claim:

1. In a mechanical movement, a member

mounted to reciprocate, a gear mounted eccentrically on said member, a second gear mounted to revolve eccentrically, and an idler meshing with said gears.

2. In a mechanical movement, a casing, a member guided by said casing and mounted to reciprocate therein, a gear mounted eccentrically on said member, a second gear mounted eccentrically on said casing, means for revolving said second gear on its eccentric axis, an idler meshing said gears, and means connecting the centers of said gears.

3. In a mechanical movement, a casing, a member slidably mounted in said casing, a gear mounted eccentrically on said member, a second gear mounted eccentrically on the casing, means for revolving said second gear, means connecting the centers of the two gears, and an idler carried by said means in mesh with said gears.

4. In a mechanical movement, a casing, a member slidably mounted in said casing, a gear mounted eccentrically on said member, a second gear mounted eccentrically on the casing, means for revolving said second gear, a link connecting the centers of the two gears, and an idler carried by said link and interposed between said cams.

5. In a mechanical movement, a casing, a member slidably mounted in said casing, a gear mounted eccentrically on said member, a second gear mounted eccentrically on the casing, means for revolving said gear, a transmission interposed between said means and said second gear, a link connecting the centers of the two gears, and an idler carried by said link in mesh with said gears.

6. In a jack, a casing, a post slidably mounted therein, a shaft revolvably mounted in the casing, a gear mounted eccentrically on the shaft, a second gear mounted to revolve and slide on the casing, an idler interposed between the gears, a link connecting the centers of the eccentric gears, said idler being carried by the link, means for imparting motion to the shaft, and lazy tongs anchored to said shaft and connected to the second mentioned gear and idler.

WILLIAM JOHNSON PAYNE.
